CLAIM

The ornamental design for a shovel, as shown and described.

DESCRIPTION

FIG. 1 is a perspective view of a shovel, the scoop portion being shown in broken lines;

FIG. 2 is a front view thereof, the scoop portion being shown in broken lines;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The portions shown in broken lines are included for illustrative purposes only and form no part of the claimed design.
